UNITED STATES PATENT OFFICE

2,599,402

ORE-WASHING APPARATUS

Roy B. Lindsey, Phoenix, Ariz.

Application June 5, 1950, Serial No. 166,224

1 Claim. (Cl. 209—44)

1

This invention relates to ore washing apparatus and has for its primary object to recover from ore the heavier valuable substances.

Another object is to enable the separation of the valuable products from the remaining products of ore in a continuous uninterrupted process which requires but a minimum amount of labor.

The above and other objects may be attained by employing this invention which embodies among its features a trommel having a perforate and an imperforate section with the ore introduced into the imperforate section in which it is moved by a spiral baffle toward the perforate section, means for introducing wash water into the trommel for loosening and scrubbing the ore in order that the valuable products may be freed from the undesirable material and discharged into the perforate portion of the trommel, and a trough mounted below the trommel into which the material which passes through the perforated section of the trommel is received together with a portion of the wash water, means for rocking the receiving trough, and a baffle adjacent the end of the receiving trough behind which the heavier valuable products are collected for subsequent removal by hand.

Other features include means for adjusting the inclination of the trommel so as to enable the level at which the wash water is discharged therefrom to be varied, corrugations in the bottom of the inclined trough over which the wash water containing the material to be separated is continuously agitated, and means at the lower end of the inclined trough and extending above the baffle for aiding in the removal of the valueless products.

In the drawings:

Figure 1 is a side view of an ore washing apparatus embodying the features of this invention.

Figure 2 is an end view of the feeding end of the apparatus.

Figure 3 is an end view of the discharge end of the apparatus.

Figure 4 is a vertical sectional view taken substantially along the line 4—4 of Figure 2.

Figure 5 is a vertical sectional view taken substantially along the line 5—5 of Figure 1.

Figure 6 is a transverse sectional view taken substantially along the line 6—6 of Figure 1, and

Figure 7 is an enlarged transverse sectional view taken substantially along the line 7—7 of Figure 1.

Referring to the drawings in detail a frame designated generally 10 comprises horizontal side

bars 12 which are joined adjacent opposite ends by end bars 14. In the preferred form of the invention the frame 10 is supported on suitable legs 16, and mounted on the frame are cross members 18 and 20 which lie transversely of the frame in spaced parallel relation intermediate the ends thereof. Similar cross members 22 extend across the frame 10 adjacent opposite ends and mounted on the cross members 18, 20 and 22 adjacent one side of the frame 10 are bearings 24 in which a drive shaft 26 is mounted to rotate. This drive shaft is equipped at one end with a suitable drive pulley 28 and carries at its opposite end a pulley 30, the purpose of which will be more fully hereinafter explained.

Mounted in a suitable bearing 32 carried by the cross member 18 is an idler shaft 34 which extends substantially parallel to the shaft 26 and is also mounted in a bearing 38 which is mounted for longitudinal sliding movement on the cross member 20. The top web of the cross member 20 is provided with a longitudinally extending elongated slot 40, and depending from the under side of the bearing 38 and extending through said slot is an ear 42 having an internally screw threaded opening extending therethrough in parallel relation to the slot 40. Secured to the under side of the top of the cross member 20 and depending therefrom is a bearing block 44 in which one end of a screw 46 is mounted to rotate. This screw extends through the opening in the ear 42 in threaded engagement with the threads therein, and projects longitudinally beneath the top of the cross member 20 through a bearing block 48 carried thereby, and fixed to the end of the screw 46 remote from the bearing block 44 is a hand crank 50 by means of which the screw may be rotated to move the bearing block longitudinally on the frame member 20.

Mounted for rotation on the idler shaft 34 are idler rollers 52, and secured to the shaft 26 are grooved drive rollers 54. These rollers 52 and 54 form the support for a trommel designated generally 56 which is equipped at spaced points with bands 58 and 60. It will thus be seen that when the drive shaft 26 is set into motion, the drive rollers 54 contacting the bands 58 and 60 will cause the trommel 56 to rotate.

The trommel above referred to comprises a cylinder having an imperforate section 62 and a perforated section 64. Carried at circumferentially spaced points on the interior of the imperforate section 62 are longitudinally extending baffles or weirs 66 which serve to agitate the ore deposited in the trommel and carry it up the

sides thereof as the trommel rotates so that it will fall back and become broken to facilitate the extraction of the valuable products therefrom. Carried by the wall of the imperforate section 62 of the trommel 56 and extending thereto is a spiral baffle or weir 68 which as illustrated is relatively shallow adjacent the receiving end of the trommel but which increases in depth as at 70 adjacent the perforate portion 64 of the trommel 56. This spiral weir 68 serves to cause the ore deposited within the trommel 56 to be advanced through the imperforate section 62 toward the perforate section 64 thereof as the trommel rotates. The end of the imperforate section 62 of the trommel 56 remote from the perforate section 64 thereof is provided with an end closure 72 which is formed with an axial opening 74, and surrounding the axial opening 74 is an inwardly extending collar 76 into which the discharge end of a funnel shaped hopper 78 is extended. This hopper 78 serves to receive the ore to be treated, and discharges said ore into the imperforate section 62 of the trommel 56 as will be readily understood upon reference to Figure 1. Extending outwardly from the end closure 72 in surrounding relation with the opening 74 is a conical member 80 which serves to direct wash water flowing out of the imperforate section 62 of the trommel 56 through the opening 74 into a waste trough 82 which discharges into any convenient waste receptacle.

Mounted on the frame 10 and extending longitudinally thereof beneath the trommel 56 is a collecting trough 84, the bottom of which slopes downwardly from the end thereof adjacent the extreme outer end of the perforate section 64 of the trommel 56, so that material passing through the perforations of the perforate section 64 will be collected in the trough 84 and discharged therefrom at the end thereof adjacent the feed hopper 78.

Mounted in the frame 10 below the collecting trough 84, and inclining downwardly from the discharge end thereof toward the receiving end thereof is a shaft 86, and mounted for rocking motion of said shaft is a downwardly inclined rocking trough designated generally 88. This trough is provided with a generally arcuate bottom 90 which is provided at peripherally spaced points with inwardly extending corrugations 92 which form baffles across which the wash water containing the ore to be separated is continuously agitated during the rocking of the trough 88. The end of the trough 88 adjacent the discharge end of the trough 84 is closed by an end wall 92, so as to prevent the material leaving the discharge end of the trough 84 from flowing out of the upper end of the inclined rocking trough 88. A weir or baffle 96 bridges the lower end of the rocking trough 88 as will be readily understood upon reference to the drawings. As illustrated the corrugations 92 terminate in spaced relation to the weir 96 so that the lower section 98 of the bottom 90 of the trough 88 is relatively smooth, and if so desired suitable depressions or pockets 100 may be formed in the smooth portion 98 in which the valuable products are collected behind the weir 96.

Suspended on suitable bearing brackets 102 beneath the frame 10, and above of the rocking trough 88 is a shaft 104 carrying a screw 106 which projects into the lower end of the trough 88 above the weir 96, and when operated this screw serves to improve the rapidity with which the products of lesser value are extracted from

the trough. A suitable pulley 108 is carried by the shaft 104 and driving connection is established between the pulleys 30 and 108 through the medium of an endless belt 110.

In order to supply wash water to the apparatus I provide a supply pipe 112 which is connected through a suitable valve 114 to a discharge pipe 116 which opens into the hopper 78. The supply pipe 112 is also coupled through the medium of the conventional valve 118 with a pipe 120 which enters the open end of the perforate section 64 of the trommel 56 and has its discharge end located within the imperforate section 62 of said trommel so that when the valve 118 is opened, water will be admitted to the imperforate section of the trommel in a direction counter to the flow of the ore therethrough. A spray pipe 122 extends into the open end of the perforate section 64 of the trommel 56 and is coupled through a conventional valve 124 with the supply pipe 112. It will thus be seen that by opening the valve 124 the washed material leaving the imperforate section 62 of the trommel 56 may be further sprayed, so that the material which passed through the perforate section 64, and the water sprayed through the pipe 122 will be collected in the trough 84, to be discharged from the discharge end thereof into the rocking trough 88.

Mounted for rotary motion in suitable bearings 126 carried by the frame 10 is a crank shaft 128 having a crank 130 to which a connecting rod 132 is rotatably connected at 134. The opposite end of the connecting rod 132 is coupled to a bar 136 which is rockably supported at 138 on the end 94 of the trough 88. Fixed to the trough and extending laterally therefrom is a plate 138 having an arcuate slot 140 therein which lies concentric about the rocking connection 138, and carried by the bar 136 and extending through the slot 140 is a screw 142 which holds the bar 136 in various adjusted positions relative to the rocking trough 88 to thereby control the length of stroke imparted by the connecting rod to the rocking trough 88, so that its magnitude of motion may be varied to suit varying requirements.

In use ore to be washed is deposited in the hopper 78 and flows through the funnel shaped portion thereof into the interior of the imperforate portion of the trommel 56. Upon opening the valve 114, and rotating the drive shaft 26, it will be evident that the trommel 56 will rotate about its axis thus causing the ore to be tumbled within the imperforate portion 62 of the trommel by the baffles 68. With the valve 118 opened, it will be evident that wash water will flow through the pipe 120 into the imperforate portion 62 of the trommel 56, and as the trommel rotates, the ore contained therein will be advanced by the spiral baffle 68 toward the perforate portion 64 of the trommel and counter to the flow of water into the trommel through the pipe 120. Owing to the height of the spiral baffles 68 at their ends 70, and the height of the opening 74 in the end closure 72 of the imperforate portion 62 of the trommel 56, it will be evident that water will be trapped within the trommel and may escape only by overflowing through the opening 74 to be discharged into the waste trough 82. Obviously by rotating the hand screw 46, the roller 52 supporting the trommel 56 adjacent the junction of the imperforate portion 62 with the perforate portion 64, the roller 52 will cause the trommel to raise or lower according to the direction of rotation of the screw 46. By thus adjusting the tilt

of the trommel 56, it will be evident that the volume of water contained in the imperforate portion thereof may be regulated. As the washed ore is discharged by the spiral baffle 68 into the perforate portion 64 of the trommel 56, it is sprayed by water issuing from the sprayed pipe 22 and the ore which passes through the perforations in the perforated portion 64 is received in the trough 84 together with the spray water. Flowing with the water in the trough 84 to the discharge end thereof, the ore and water are received in the upper end of the rocking trough 88 in which the ore and water are rocked across the corrugations 92 to further separate the heavier valuable contents of the ore from the remainder thereof. Flowing downwardly in the trough 88, the ore and water reach the lower end thereof with the water with lighter contents of the ore flowing over the upper edge of the weir 96, while the heavier valuable products will be arrested by the weir and retained in the trough 88 for subsequent removal. Obviously the heavier products will also enter the pockets or depressions 100 and thus the capacity of the trough 88 for retaining the valuable products is increased. Obviously the operation may be continued indefinitely by continually feeding ore into the hopper 78 until such time as the space in the trough 88 behind the weir 96 becomes filled with the valuable products.

While in the foregoing there has been shown and described the preferred form of this invention, it is to be understood that minor changes in the details of construction, combination and arrangement of parts may be resorted to without departing from the spirit and scope of the invention as claimed.

I claim:

In an ore washing apparatus, including a cylindrical, horizontally rotatable trommel having a front end imperforate section and a rear end perforate section, a trough of substantially V-shape cross-section and a width somewhat greater than the diameter of the trommel, said trough underlying the under side of the trommel and sloping downwardly and forwardly for receiving the washed ore discharged through the perforations of the perforate section thereof, a second trough of substantially arcuate cross-section underlying the longitudinal central portion of the first trough and sloping downwardly and rearwardly to receive the washed ore from the forward end of the first trough, means for imparting a lateral rocking motion to the second

trough, a baffle within the second trough at each side of the longitudinal center thereof for agitating the washed ore in its passage along the same, said baffles terminating short of the rear end of the second trough, means in the bottom of the second trough beyond the terminal ends of the baffles for collecting the heavier value containing ore from the wash water as it and the lighter value free ore overflows the trough end, and a rotary spiral element projecting angularly into the rear end of the second trough to assist in the discharge of the wash water and the lighter ore from the trough end.

ROY B. LINDSEY.
